SECURITY AND MOTOR CONTROL DEVICE

James A. Spencer, Teaneck, N. J., assignor to
Radio Corporation of America, a corporation of
Delaware

Application November 23, 1938, Serial No. 241,942

14 Claims. (Cl. 178—22)

This invention relates to telegraph systems either wire or radio. Telegraph messages when radiated into the air in accordance with the code sent out by an automatic transmitting head can be picked up by a receiver and interpreted by any one familiar with the code. In wire telegraphy messages likewise can be surreptitiously received and interpreted by tapping the wire over which the message is sent. It is therefore desirable to break up the message into unintelligible combinations so that unauthorized persons cannot interpret the messages.

It is an object of this invention to so change the communication signals sent over the air, or a conducting wire, that the message is unintelligible until it is transformed back into its original condition.

More specifically, it is an object of the invention to periodically reverse in accordance with a predetermined plan, the signal currents being transmitted and received.

Other objects will appear in the following description, reference being had to the drawings, in which:

Fig. 1 is a diagrammatic illustration of the transmitting circuit.

Fig. 2 is a diagrammatic illustration of the receiving circuit.

Fig. 3 shows graphs of the signals in my improved system.

Referring to Fig. 1, CR indicates generally a series of relays arranged to operate in succession to serve as a counting device for reversing the transmitted current after a predetermined time. 1 indicates the transmitting relay operated by the automatic transmitter diagrammatically indicated at 2. This automatic tape transmitter is operated at a given constant speed to alternately elevate two plungers against a tape, having a series of spaced holes previously punched in accordance with the message that is to be transmitted. Since this type of tape transmitter is well known in the art the action is simulated in the diagrammatic illustration by a pivoted lever 3 moving about its center point to alternately engage contacts 4 and 5, whenever the perforations in the tape permit the contact to be made.

The relay 1 is polarized so that current through coil 6 and 7 moves the tongue in opposite directions to open and close the switch.

The switch tongue in relay 9 in one position engages the positive terminal 10 and in the other position the negative terminal 11. Relay 9 is a modified Gulstad relay that differs from the standard Gulstad relay chiefly in having a hold-

ing coil 12 that prevents the tongue 13 from vibrating at keying frequency while it is energized. When the coil 12 is deenergized the tongue 13 can then move in response to the impulses of coils 13' and 14.

Current for the coils 13' and 14 is supplied from the contacts 10 and 11 through conductor 15. The coils are grounded at 16.

Reference character 17 indicates generally a frequency control relay that is also of the Gulstad type except that additional coils 18 supplied from the transmitting relay 1 correct the relay for any minute variation in frequency and phase by pulling the switch tongue into step with the impulses sent out by the transmitting relay 1. The method of operation of the relay 17 is as follows:

With the switch tongue 19 in engagement with the positive marking contact 20, current passes through conductor 21 to coil 22 through a suitable resistance 23, coil 24, to ground and back to the mid terminal of the battery 26. At the same time current from conductor 21 passes through coil 27 to the condenser 28, resistance 29, to ground and to the intermediate terminal of the battery 26. The coils 22 and 27 act in opposition at this time so that while coil 22 tends to force the switch tongue away from contact 20, coil 27 tends to hold it against the contact 20. The magnetic pull of coil 27 predominates at first because of the rush of current through condenser 28. This charging current, of course, diminishes with time while the current through coil 22 builds up with time because of the inductance in the circuit. When the current through coil 27 stops or is sufficiently reduced, coil 22 predominates and pulls the switch tongue 19 towards contact 25. As soon as the switch tongue leaves contact 20 the circuit is interrupted and the condenser 28 instantly discharges through coil 27 in the reverse direction passing also through coil 22 and the resistances 23 and 29. This flow of current, it will be noted, is in the direction to move the switch tongue 19 over against the contact 25 which it engages before the current dies down.

The currents through coils 22 and 27 are reversed when contact is made with terminal 25 because this is the negative terminal of the battery. With this reverse of current, coil 27 holds the tongue 19 in engagement with terminal 25 while the condenser 28 is charging, and coil 22 attempts to open the contact but at first coil 27 predominates. When the condenser 28 is charged or reaches a certain stage of charge, the repel-

lent force of coil 22 predominates and the switch tongue 19 is thrust toward the contact 29 and this action is aided, as before, by the discharge current of the condenser through the coils.

The relay 17 thus oscillates at a predetermined frequency depending upon the capacity of the condenser, the inductance of the coils, the value of the resistances and the potential of the battery. By proper adjustment any desired frequency of vibration may be produced. This will be practically constant though there would be a tendency to vary slightly in frequency or in phase. The coil 18, however, will delay or speed up the action sufficiently to hold the relay in step with the keying speed of the automatic tape transmitter 2.

The relay 9 also is adjusted so that it tends to oscillate in step with the keying speed of the transmitter 2 in exactly the same way as relay 17 but the tongue can move only when coil 12 is deenergized. This is deenergized only at the end of the operation of the bank of timing or counting relays CR but it is immediately energized again on deenergization of magnet VIII so the switch tongue 13 makes only one swing against the opposite contact.

It will be seen that the vibration of switch tongue 19 changes the direction of flow of current through coil 24 of the polar relay causing the switch 30 to vibrate in unison with the reversal of current and to alternately engage the marking and spacing contacts 31 and 32. These contacts each alternately energize one-half of the bank of timing or counting coils CR in succession, one-half through conductor 33 and the other through conductor 34. The transmitter relays are not polarized so the reversed and unversed current operate the coils in the same way. The operation of the transmitting system will now be explained.

It will be assumed that tongue 13 is in engagement with contact 10 when key lever 3 engages contact 4. Switch 35 is closed at this time and coil 12 energized. This puts positive current through coil 6 which throws the transmitting relay tongue 36 into engagement with the positive contact 37. This will send out a pulse in accordance with the signal through the transmitting apparatus indicated by the tone keyer 38 and radio transmitter 39. This is marking current as tongue 19 is in engagement with the marking contact 20.

When the lever 3 of tape transmitter 2 engages contact 5 the polarized relay tongue 36 will be thrown against the blank contact 40 and no current will be sent out through the radio transmitter. Positive pulses are thus being used by the tape transmitter for marking and negative for spacing, but this is reversed periodically by the counting relays CR, the operation of which will now be referred to in detail.

As soon as the marking contact was made with contact 20, as first referred to, coil 24 of relay 17 threw switch tongue 30 into engagement with the marking contact 31. Current from contact 19 of relay 9 and conductor 41 then passed through switch contact 31 to conductor 33, conductor 42, coil 43 of relay I, conductor 44 and back-switch 44' of relay VIII to ground. Relay I was thus energized when the first marking contact was made in relay 17. The operation of relay I closes switch 46 and coil II is energized when the relay tongue swings on to spacing contact 32. This energization is produced by current flowing through conductor 34, the coil of

relay II, switch 46, conductor 44 and switch 44' to ground. Relay II operates and closes switch 47.

It should be explained at this time that relays I and II, as well as each of the other counting relays, are held energized by holding coils, the circuit of which is closed at 49 by the operation of a preceding relay.

It will not be necessary to trace the circuit of the remaining coils of the counting relays as it will be seen that these relays are energized progressively by the vibrating tongue 30 and switches 41, 50, 60, 70, 71 and 78.

The energizing and holding currents of the timing relays pass through the contact 44'. Therefore, when relay VIII is energized the circuits of all the timing relays are open by operation of this switch. This at once deenergizes all of them and this immediately recloses switches 35 and 44'. The time taken to energize the series of relays may be made anything desired. While the series of relays RC were being energized the transmitter was sending out positive current for marking.

Just as soon as switch 35 opens, coil 12 is deenergized momentarily and this happens while the switch tongue 30 is starting towards space contact 32. Therefore, switch tongue 13, being now free to move, swings into engagement with its spacing contact 11. However, switch tongue 13 is forced to remain against contact 11 by the immediate re-energization of coil 12 by reclosure of switch 35.

The timing relays I to VIII are again energized progressively and during this period negative current is sent into the coils 6 and 7 of transmitting relay I. This means, of course, that the current will be reversed in these coils. Whenever a marking pulse is sent out by the tape transmitter 2 the relay tongue 36 will be thrown against dead contact 40 and when a spacing pulse is sent out relay tongue 36 will be thrown against the marking contact 37. This sends current to the antenna for the spaces of the signal.

In the embodiment shown the reversal of mark and space indications takes place every four dot-cycles and the effect is shown in Fig. 3 where graph A represents a normal signal for the word "and." Graph B represents the same signal sent out by my improvement, with reversals taking place every four dot cycles. From a to b unversed signals are transmitted. From b to c the signals are reversed. At the point c the signals are again normal and so on. The signal radiated by the antenna is indicated by graph C.

The receiver of Fig. 2 is arranged with a series of counting relays CR, a frequency control relay 17, a transfer relay 9 and line relay generally indicated at 81, that are the same or practically the same as the similar relays in the transmitting end of the system.

The vibrations of the relay 17 are maintained in exact phase and synchronism with the transmitter by the pulses received through the receiving apparatus 82, 83, line 84, condenser 85 to coil 18. The switch tongue of the transfer relay 9 is prevented from continually oscillating by the holding coil 12 energized through back contacts 44' of the relay VIII. Parts in the receiving circuit of Fig. 2 that are similar to those of the transmitting system of Fig. 1 have in general similar reference characters.

In the receiving circuit, the polarized line relay consists of coils 88 and 89 which when ener-

gized move the switch tongue in opposite directions. Coil 88 predominates over coil 89.

When the rectified signal D is received, the current pulses passing over line 84 will cause switch tongue 90 to engage contact 91. At this time tongue 13 is held against the positive contact and positive current will traverse coil 92 of the polarized recorder. Stylus 94 will be attracted toward coil 92. The moving tape 95 will then receive a "mark" record. When no current is being received over line 84 in the spaces of the signal the battery coil 89 throws the switch tongue 90 into engagement with contact 96. This energizes coil 93 which attracts stylus 94 into its spacing position. The recorder will record the signal at this time as given between the points a and b of graph E.

When reversed signals between b and c of graph D are being received over line 84, switch tongue 90 will be moved against contact 91 for 20 the spaces. At the point b of graph D the counting or timing relays CR have just completed their operation and the momentary interruption of current through coil 12 by the opening of switch 44 permitted tongue 13 to move against the negative terminal where it was held by the immediate re-energization of this coil. Therefore, at point b negative current commences to operate the recorder. This current passes from contact 91 through coil 92. The stylus is thrown away from the coil since the current is now reversed. A space will thus be formed. When the current ceases to flow in the line 84 at the termination of the space, coil 89 throws the tongue against contact 96. This puts negative current through coil 93 and stylus 94 is repelled toward coil 92. This produces a "mark" record. Thus, the signals reversed at the transmitter are again reversed at the recorder and normal signals are produced as in graph E.

When the transmission of signals is interrupted for a substantial length of time there will be no current at the receiving end in coil 18 of relay 17 to cause the timing relays to operate in exact phase and synchronism with the timing relays at the transmitter. To prevent the transmitting and receiving relays from getting out of step during interruptions, I provide slow release relays 97 which will not operate during the short spacing intervals between the code characters but which will operate when the transmission and reception ceases. When the slow release relays operate, the circuits of the locking coils 12 and the holding coils of the counting relays are opened by de-energization of coils 98. While the transfer relay and the counting relays at the transmitter and receiver still vibrate, the counting relays are inoperative until signal current again energizes the slow release relays. When this happens the coils 18 pull the receiving relays 9 and 17 into step with the transmitting relays. The counting relays at the transmitter and receiver thus start in synchronism.

While I have described my invention in connection with a simplex system, it will be apparent that it can be used equally as well in multiplex systems, for example, such as shown in Mathes Patent No. 1,979,484, November 6, 1934, and when so used the relays 17 and 19 can be used to control the distributors, as they are vibrating in 70 synchronism and phase with the keying speed.

I have shown eight timing relays but any number from two on up may be used equally as well. Various other modifications may be used without departing from the spirit of the invention.

Having described my invention, what I claim is:

1. In a secrecy telegraph system, means for making mark and space indications for transmitting a message and means for automatically interchanging the mark and space indications at predetermined intervals.
2. In a secrecy telegraph system, means for making mark indications by current of one character and a space by current of another character and means to automatically interchange the application of said currents for interchanging the mark and space indications.
3. In a secrecy telegraph system, means for making mark and space indications by pulses of different signs and means for reversing the sign of said pulses for automatically interchanging the mark and space indications after predetermined intervals.
4. In a secrecy telegraph system, for reception of signals having mark and space indications periodically interchanged, means for receiving the indications and means for automatically interchanging the mark and space indications at said predetermined intervals.
5. In a secrecy telegraph system, a transmitter switch, means to operate said switch for sending current of one character for marking indications, and a timing mechanism acting at predetermined intervals for automatically causing said means to operate said switch for sending current of the same character for space indications.
6. In a secrecy telegraph system, a source of current supply, a polar switch having mark and space positions, two coils for operating said switch, a keying device for sending current through one of said coils for moving the switch to one position and through the other for moving it to the other position, and timing means acting at predetermined intervals for alternately connecting said keying device to the positive and negative terminals of said supply.
7. In a secrecy telegraph system, a sending station, a code transmitter at said station for making mark and space indications, means at 45 said station for automatically interchanging the mark and space indications of the code transmitter at predetermined intervals, a receiving station and means at the receiving station for automatically interchanging the mark and space indications in synchronism with the first mentioned means.
8. In a secrecy telegraph system, a sending station, a code transmitter at said station for making mark and space indications, means at said station for automatically interchanging the mark and space indications of the code transmitter at predetermined intervals, a receiving station, a recorder at the receiving station and means at the receiving station for automatically causing 50 the recorder to interchange the mark and space indications in synchronism with the changes made by the first mentioned means.
9. In a secrecy telegraph system, a sending station, a code transmitter at said station for making mark and space indications, a timing mechanism at said station for automatically interchanging the mark and space indications of the code transmitter at predetermined intervals, a receiving station, timing mechanism at the receiving station for automatically interchanging the mark and space indications in synchronism with the first mentioned means and means for de-energizing the last mentioned timing mechanism a predetermined time after the 75 received signal energy ceases.

10. In a secrecy telegraph system, a sending station, a code transmitter at said station for making current variations indicating marks and spaces, a receiving station, means at the sending station for automatically interchanging the current variations to send space variations for marks and mark variations for spaces and means at the receiving station for automatically altering the recording means to thereupon record marks for spaces and spaces for marks.

11. In a secrecy telegraph system, a polar relay for making mark and space indications, a source of voltage, a reversing switch, a code transmitter for applying energizing voltage to said relay from said source through said switch, a vibrator operating at constant frequency applying force tending to cause the switch to operate at a constant frequency, means for preventing the vibrator from operating said switch and means operating at predetermined intervals for neutralizing the action of the first mentioned means to permit the vibrator to operate the reversing switch.

12. In a secrecy telegraph system, a polar relay for making mark and space indications, a source of voltage, a reversing switch, a code transmitter for applying energizing voltage to said relay from said source through said switch, a vibrator operating at constant frequency applying force tending to cause the switch to operate at a constant frequency, means for preventing the vibrator from operating said switch and means operating during one of a predetermined number of half cycles of the vibrator for neutralizing the action of the first mentioned means to permit the vibrator to operate the reversing switch during such half cycle only.

13. In a secrecy telegraph system for reception of signals having marks and spaces periodically interchanged at the transmitter, a receiver, electromagnetic means connected to the receiver for making alternate mark and space indications when voltage of one sign is applied thereto and for reversing said indications when voltage of opposite sign is applied thereto, a reversing switch, a source of voltage supply connected to said means through said switch and means for operating said reversing switch when the marks and spaces in the receiver are reversed.

14. In a secrecy telegraph system, a polar relay for making mark and space indications, a source of voltage, a reversing switch, a transmitter for applying energizing voltage to said relay from said source through said reversing switch, a vibrator operating at a constant frequency tending to cause said switch to reverse at said frequency the operating voltage applied to the relay, a magnet when energized preventing said vibrator from operating said switch and means operating at predetermined intervals for de-energizing said magnet for a half cycle of the frequency of said vibrator to permit it to operate said reversing switch, a recorder having electromagnetic means for making marks and spaces when voltage of one sign is applied thereto and for reversing the marks and spaces when voltage of opposite sign is applied thereto and means at the receiver for reversing the voltage applied to the electromagnetic means when the reversing switch at the transmitter is operated.
